UNITED STATES PATENT OFFICE

ADOLPH A. THOMAS, OF NEW YORK, N. Y.

ELECTROMAGNETIC ACOUSTIC DEVICE

Application filed December 31, 1926, Serial No. 158,134. Renewed November 14, 1927.

My invention is for a new and improved sound transmitter and receiver of the electromagnetic type, and its object is to provide an instrument characterized by simplicity of 5 construction and sensitiveness in operation.

When my invention is constructed as an electric phonograph reproducer, it is of special advantage in playing the new type of finely grooved records in which the spiral track 10 runs to several hundred lines per inch and which play for thirty minutes and longer.

The essential feature of my invention comprises an elastic magnetic ring supported at its circumference and deformable in its own 15 plane for vibratory movement. When my invention is used as an acoustic device, a vibratory acoustic member is so connected to the ring as to deform it in its own plane. The vibrations of the magnet ring produce 20 flux variations in a coil for generating electric impulses. Or, if the coil is connected in a circuit of electric impulses, these will vibrate the elastic magnetic ring and the connected member. The magnetic ring is sup- 25 ported at a fixed point, and a suitable actuating member is connected to the ring at a point which preferably is diametrically opposite the fixed point of support. As the connected member vibrates, the normal shape 30 of the ring is deformed, being flattened in one direction and the other. Electromagnetic means associated with the ring produce electric impulses in accordance with the vibrations of the ring, and these impulses, 35 which are electrical representations of the movements of the actuating member, are utilized to operate suitable loudspeaker mechanism or to perform any other useful function. The elastic magnetic ring may also 40 act as a centering or restoring spring for the connected vibratory member. In the basic aspect of my invention, this elastic ring may operate as a vibratory armature in relation to the poles of a field magnet, or it may be 45 constructed as a permanent magnet having polar ends or pole pieces arranged to vary the airgap between them and a stationary armature as the ring vibrates. This construction, when used in the form of electric 50 reproducer, is so sensitive in operation as to

reproduce correctly the minutest movements of the stylus. Conversely, when the elastic ring is vibrated by current impulses in an electromagnetic coil, the device may be used as a phonographic recording tool. 55

So that those skilled in the art may fully understand my invention and practise the same, I shall describe in detail several illustrative embodiments which best express my ideas at this time as applied to phonograph 60 reproducers. In the accompanying drawings—

Figs. 1-7 illustrate in a diagrammatic way how the underlying principle of my invention may be embodied in various forms; 65

Fig. 8 shows in cross-section an electric reproducer constructed in accordance with the diagrammatic representation of Fig. 4;

Fig. 9 is a sectional view on line 9-9 of Fig. 8; 70

Fig. 10 is a sectional view on line 10-10 of Fig. 8;

Fig. 11 shows in cross-section a modification particularly adapted to play vertical-cut records of the Edison type; 75

Fig. 12 is a plan view approximately on section line 12-12 of Fig. 11; and

Fig. 13 is a diagrammatic representation of an electric transmission system between the reproducer and loudspeaker mechanism. 80

Before taking up a detailed description of the drawings, I want to make it plain that the diagrammatic views in Figs. 1-7 do not show the various parts in correct mechanical proportions, but these figures are merely intended to illustrate the principle of the invention as clearly as possible. In the structural views of Figs. 8-12, the parts are shown on a greatly exaggerated scale for the sake of clearness, and these figures are therefore not 85 to be interpreted as shop drawings.

The basic principle of my invention will be readily understood from a consideration of Figs. 1 and 2, where an elastic magnetic ring 10 is connected at point 11 to a fixed support 12. A stylus lever 13 is pivoted at 14 and carries a stylus 15 for playing records. The lever 13 is connected at 16 to the magnetic ring 10. The points 11 and 16 are substantially 90 on a diametric line of ring 10. A magnet M 100

is operatively associated with the magnetic ring 10. To simplify the drawings, I have illustrated the magnet as a straight bar arranged within the ring on a diameter substantially at right angles to the diameter of connecting points 11 and 16. This arrangement is, of course, purely diagrammatic and need not be followed in the actual construction of the device. The pole pieces N and S of magnet M terminate in proximity to the magnetic ring 10 at diametrically opposite points. A coil C is mounted on magnet M so as to be influenced by changes in magnetic flux through the pole pieces.

The armature ring 10 is of elastic magnetic material having low permeability and is capable of being distorted in its own plane. The normal position of ring 10 and stylus arm 13 is shown in full lines in Fig. 2. As the arm 13 moves into position 13^a, the elastic ring 10 is distorted in its own plane into an elliptical shape, as roughly indicated by dotted line 10^a, and it moves away from the polar ends of magnet M at the points x in Fig. 1. When the arm 13 vibrates in the opposite direction, as indicated by dotted line 13^b in Fig. 2, the ring 10 is flattened vertically into the elliptical shape 10^b and moves closer to the magnetic poles, as indicated at points y. If the positions 13^a and 13^b are assumed to be the extreme opposite positions of the stylus arm 13 in the playing of a record; there will occur an almost infinite number of intermediate positions of the armature ring 10 in relation to the pole pieces of the magnet. These vibratory movements of the elastic armature ring 10 produce current impulses in coil C in accordance with the vibrations of the record-playing stylus. The current impulses thus produced are utilized to operate suitable loudspeaker mechanism. A simple form of electric transmission system will later be explained by way of example.

In the actual instrument, the movements of stylus arm 13 and armature ring 10 are considerably less than indicated in a rough way by the dotted lines of Figs. 1 and 2. In fact, those movements are so minute as to be undetectable by the naked eye, but it was necessary to exaggerate Figs. 1 and 2 for the sake of clearness. The armature ring 10 is so dimensioned that it transmits the magnetic flux without saturation. Each half of the ring carries approximately one-half of the field flux, theoretically speaking; in actual practice, however, there will probably be variations from this rule without affecting the operation of the reproducer.

It will be noticed that the vibrations of stylus 13 are transmitted in amplified ratio to the armature ring 10. In practice, this ratio would be about 1:3, but I mention these figures merely by way of example. The action of the magnetic ring 10 is so sensitive that the

minutest movements of the stylus points produce current impulses in coil C. Even though these impulses are exceedingly weak, they can be amplified, as through radio vacuum tubes, to operate a loudspeaking diaphragm with requisite volume.

The elastic armature ring 10 also functions as a restoring or centering spring for the stylus arm, so that no separate spring is needed for that purpose. The degree of resiliency of ring 10 is such that it offers the right amount of mechanical resistance to the vibrations of the stylus arm 13. I scarcely need add that in Figs. 1 and 2, as well as in the other views, the size of ring 10 has been grossly exaggerated in relation to the other parts. As actually constructed, this ring may be less than one inch in diameter.

In the diagrammatic illustration of Fig. 3, the magnet associated with the armature ring 10 has pole pieces 17 and 18 arranged outside the ring on a diameter approximately at right angles to the diametric line of connecting points 11 and 16. On pole piece 17 is a coil 19, and there may be a coil 20 on pole piece 18. Otherwise, what has been said in connection with Figs. 1 and 2 is fully applicable to Fig. 3.

In Fig. 4, the magnet is so constructed as to have two bifurcated pole pieces, with a coil on a bifurcation of each pole piece. Thus, one pole piece comprises the limbs or bifurcations 21 and 21', and the other pole piece comprises limbs 22 and 22'. On the polar limb 21' is a coil 23, and on polar limb 22' is a coil 24. The bifurcations of each pole piece are so spaced as to provide an airgap 25, and the two airgaps are arranged on a diametric line approximately at right angles to the diameter connecting the points 11 and 16. In the normal position of the parts, the armature ring 10 is about midway of the two airgaps 25, although that is not absolutely necessary. When the stylus arm 13 vibrates toward the left (as viewed in Fig. 4), the armature ring is moved toward the outer polar limbs 21 and 22, so that the magnetic flux through the coils on the inner polar limbs 21' and 22' is decreased. When the stylus arm moves toward the right, the magnetic ring 10 approaches the inner polar limbs 21' and 22', thereby increasing the flux density through coils 23 and 24. In this way, the distortional movements of the armature ring 10 produce current impulses in coils 23 and 24, which are supposed to be properly connected in circuit, as will be understood by those skilled in this art.

In Fig. 5, the magnet M is arranged along the diameter connecting the points 11 and 16. One pole of the magnet is in direct magnetic contact with the armature ring 10 at the point 11, while the other pole is spaced from the armature ring by an airgap 26. As the stylus arm 13 vibrates toward the magnet, the airgap 26 is decreased, and when the arm moves

away from the magnet, the airgap is increased. These variations in the airgap produce current impulses in coil C in accordance with the vibrations of the stylus. In other respects, what has been said about Figs. 1 and 2 may be considered applicable to Fig. 5.

In Fig. 6, the elastic ring 10 forms a permanent steel magnet provided with pole pieces 27 and 28 of low magnetic permeability. These pole pieces are arranged in the diameter of points 11 and 16 and are separated by an airgap 29. The pole piece 27 is fixed, but the pole piece 28 vibrates with the magnetic ring 10 to produce variations in airgap 29 in accordance with the vibrations of stylus arm 13. The movements of pole piece 28 relative to the aligned pole piece 27 produce current impulses in coil or coils C, which are utilized to operate loudspeaking mechanism. The movable pole piece 28 is made so light as to add no impeding weight to the stylus arm.

The construction in Fig. 7 differs from Fig. 6 in that the pole pieces 27' and 28' of the elastic permanent magnet 10 are arranged along a diameter approximately at right angles to the diametric line connecting the points 11 and 16. In this construction both pole pieces are movable toward and from each other. This means that the distortional movements of ring 10 in its own plane produce amplified variations of airgap 29'. In this respect, Fig. 7 is preferable to Fig. 6, where the pole piece 27 is fixed. Otherwise, what has been said for Fig. 6 applies to Fig. 7 without the need of repetition. The pole pieces 27' and 28' are preferably of low permeability and so light in weight that the inertia of the vibratory stylus arm and connected ring 10 is not detrimentally increased.

The structural embodiment of Figs. 8, 9 and 10 is based upon the diagrammatic representation of Fig. 4. The parts are mounted in a suitable casing 30 adapted to be supported in operative position on a horizontally movable arm, as by means of a hub 31 or otherwise. In casing 30 is fixed a permanent steel magnet M', which is here shown rectangular in shape. The magnet M' may conveniently be secured to the front plate or cover 32 of the casing, as by means of screws 33, or otherwise. By making the magnet flat, it can be stamped out of a piece of sheet steel. At opposite points magnet M' is formed with polar enlargements 34, to which are secured U-shaped pole pieces 35 and 36 of low permeability. Screws 37 or other suitable fastening devices hold the pole pieces rigidly to the body of the magnet. Pole piece 35 comprises limbs or bifurcations 21 and 21', and pole piece 36 is similarly formed by limbs or bifurcations 22 and 22'. These polar bifurcations were previously mentioned in connection with Fig. 4, and the purpose of

Fig. 8 is to show how the diagrammatic arrangement of Fig. 4 may be embodied in structural form. It is not to be supposed, however, that Fig. 8 acts as a limitation on the broad idea expressed in Fig. 4, for it is manifest that the underlying idea represented diagrammatically in Fig. 4 may be structurally embodied in other forms than Fig. 8. On the inner polar limbs 21 and 22' are mounted the coils 23 and 24. The elastic armature ring 10 is secured at 11 to a lug 38 in casing 30. This lug may be cast integral with the casing wall, and is preferably recessed at 39 to receive the ring 10 in a snug fit, so as to prevent lateral movements of the ring. The casing 30 is provided at its bottom with a pair of ears for receiving the pivot bearing 14 of the stylus lever 13, which is here shown as a needle arm for playing lateral-cut records. Although the stylus 15 is represented as a pointed needle, any other form of record-playing member may be used, depending upon the type of record. The inner end of needle arm 13 is connected at 16 to the armature ring 10. In the normal position of the parts as shown in Fig. 9, the ring 10 is substantially midway of the polar airgaps 25. What has previously been said about the operation of the diagrammatic structure of Fig. 4 is fully applicable to the instrument shown in Figs. 8, 9 and 10, so that I need not repeat that part of the specification.

The modification of Figs. 11 and 12 is designed to operate on vertical-cut records of the Edison or Pathé type. In this instance, the elastic armature ring 10 is mounted in vertical position in a suitable casing 40 provided with a tubular extension 41 for mounting the reproducer on a supporting arm. The ring 10 is secured to the top of the casing 40 at the point 11, which may be a screw or rivet extending into a lug 42 projecting from the casing wall. Casing 40 carries at the bottom a pair of lugs or ears 43 for supporting a suitable pivot bearing 44, on which is mounted a lever 45. The head 46 of this lever carries a suitable stylus 47 (usually a diamond point) arranged to operate in the vertical-cut groove of a record 48. The inner end of stylus lever 45 is connected to the elastic armature ring 10 at the point 16 by means of a link 49, or in any other practical way. The connecting link 49 projects through a hole 50 in the bottom of the casing. It will be seen from Fig. 11 that the stylus vibrations are transmitted to the armature ring 10 in amplified ratio. In casing 40 is mounted a U-shaped permanent magnet 51 arranged in a horizontal plane. To accommodate this magnet, the casing 40 is provided with a lateral extension 52, which forms a shallow chamber shaped to receive the magnet 51 in a snug fit. One or more fastening members 53 may be used to secure the magnet rigidly in position. The lateral extension 52

also serves as a convenient finger piece for manipulating the reproducer into and out of playing position. The magnet 51 is provided with pole pieces 54 arranged within the plane 5 of armature ring 10 along a horizontal diameter. Either or both pole pieces may be provided with a coil C. As the stylus lever 45 vibrates in a vertical plane in the playing of a record, the horizontal diameter of armature ring 10 is varied, and the ring moves toward and away from the ends of pole pieces 54, thereby producing current impulses in coil or coils C. I need not say any more about the operation of the reproducer shown in Figs. 11 and 12, because all that was said in connection with Figs. 1 and 2 is applicable to Figs. 11 and 12, which show a structural embodiment of the idea brought out in Figs. 1 and 2.

Fig. 13 shows a simple system for transmitting the vibrations of the armature ring or magnet 10 to a loud-speaking diaphragm D. We have here an amplifying vacuum tube V, such as is common in radio-receiving circuits, this tube having a filament 55, a 20 grid 56 and a plate 57. The filament 55 is fed by a battery 58 and controlled by a rheostat 59 in the usual way. The coil C of magnet M is connected at one end to grid 56 and at the other end to one side of filament 55, so 25 that current impulses set up in the coil by the vibrations of the magnetic ring 10 produce corresponding potential changes in grid 56. The plate circuit of tube V includes a battery 60 and the primary coil 61 of transformer T. The potential variations in grid 30 56 produce amplified current impulses in primary coil 61, as will be understood by those familiar with the radio art. These amplified current impulses may be further 35 amplified by the secondary coil 62 of transformer T and transmitted to the driving unit 63 of diaphragm D. Electromagnetic driving units for loudspeaking diaphragms are well known in the art, and the diaphragm D 40 may be considered as representing any practical form of acoustic device adapted to give a phonographic reproduction of the desired volume and quality.

It will be understood that the transmission system of Fig. 13 is merely one of many arrangements that may be employed for utilizing the electric impulses of the reproducer to operate suitable acoustic apparatus.

For simplicity, I have shown the magnetic ring 10 in the form of an unbroken circle, as if it had been cut from a tube. In practice, this ring may consist of a spring strip of the proper elasticity and then bent into annular shape, which need not be a circle, but may be 55 oval, elliptical or any other practical form of curve. It should be noted that the elastic ring 10 is not an acoustic member and produces no perceptibly disturbing sounds of its own during vibration, since its function 60 65 is to generate electric impulses and not to

produce audible sounds by its mechanical movements, as a diaphragm would do.

The constructions above described are to be regarded merely as illustrative embodiments of the basic principle of my invention, and are not in the nature of restrictions or limitations. When in the claims I speak of a vibratory stylus arm (or other acoustically actuated member) connected to the elastic magnetic ring at a point diametrically opposite the fixed point of support for the ring, I do not intend to restrict these connecting points to a mathematical diameter. For the best results, the vibratory member should be connected to the magnetic ring as nearly opposite the supporting point of the ring as mechanical conditions permit, but allowance must be made in actual practice for variations of connecting point 16. Also, I want it understood that I use the expression "stylus arm" in the claims as a convenient term to indicate any practical form or construction of stylus-holding member.

Although I have illustrated and described my invention as an electric phonograph reproducer, it is evident that it may be embodied as an electric sound transmitter or receiver for telephone purposes by substituting an acoustic diaphragm for the stylus arm. Such an adaptation is within the scope and spirit of my invention. Furthermore, in the basic aspect of my invention it is immaterial what produces the vibratory movements of the elastic magnetic ring, and such movements may be converted into electric impulses for any practical purpose.

I claim as my invention:

1. An electromagnetic translating instrument comprising a magnet structure having pole pieces arranged to provide two airgaps on a substantially diametric line, an elastic magnetic ring supported at a point in its circumference and extending through said airgaps, said supporting point being substantially midway of said airgaps, a vibratory stylus member connected to said ring at a point diametrically opposite said supporting point for the ring, so that movements of said member deform the ring in its own plane and vice versa, the movements of said ring along a diameter connecting said airgaps varying the magnetic flux through said pole pieces which provide parallel magnetic paths between the magnet and the ring, and a coil influenced by the movements of the ring.

2. An electromagnetic translating instrument comprising a magnet having a pair of substantially U-shaped pole pieces having limbs arranged to provide two airgaps on a diametric line, an elastic magnetic ring supported at a point in its circumference and extending through said airgaps, said supporting point being substantially midway of said airgaps, a vibratory stylus member connected to said ring at a point diametrically oppo-

site said supporting point for the ring, so that movements of said member deform the ring in its own plane and vice versa, the movements of said ring along a diameter connecting said airgaps varying the magnetic flux through said polar limbs which provide parallel magnetic paths between the magnet and the ring, and a coil on at least one of said polar limbs to be influenced by the movements of the ring.

3. A phonographic device comprising the combination of a casing, an elastic magnetic ring supported on said casing at a fixed point in its circumference, a vibratory stylus arm pivoted to said casing and carrying a stylus member adapted to engage the surface of a record for recording thereon or reproducing therefrom, means for connecting said arm to said ring, at a point diametrically opposite the fixed point of support of said ring, a magnetic structure secured to said casing and having at least one polar end terminating in proximity to said ring to form a variable airgap, and a coil influenced by the vibrations of said ring to generate current impulses, said coil being also adapted to receive current impulses for vibrating said ring, the mounting of said stylus arm on said casing being such that the arm exerts no drag on the elastic ring when the stylus member engages a rotating record.

ADOLPH A. THOMAS.
